CAN OPENER

John J. Egan, San Francisco, Calif.

Application August 24, 1931, Serial No. 559,040

4 Claims. (Cl. 113—1)

This invention relates to improvements in can openers.

Broadly stated, the invention consists of a pair of overlapping reciprocating jaws adapted to unfold the interlocked seam holding the tops on cans.

The principal object of the invention is to open cans without cutting the material of which they are composed.

10 Another object is to eliminate the dangers of injury to the hands of the operator and burrs and splinters of metal falling into the contents of the cans.

Other objects and advantages will appear as 15 the description progresses.

In this specification and the accompanying drawings the invention is disclosed in its preferred form. It is to be understood, however, that it is not limited to this form, because it may be embodied in other forms without departing from the spirit of the invention, as defined in the claims 20 following the description.

In the three sheets of drawings:

Fig. 1 is a side elevation of a can opener of 25 the fixed type, constructed in accordance with this invention.

Fig. 2 is a front view of the same.

Fig. 3 is a horizontal section of the same, taken on the line III—III, Fig. 1.

30 Fig. 4 is a vertical section taken on the line IV—IV.

Fig. 5 is an enlarged detail in side elevation of the operating jaws, diagrammatically illustrating the manner in which the flanged, interlocked 35 seam is unfolded.

Fig. 6 is a fragmentary detail in vertical section illustrating the first step in unfolding the interlocked seam.

Fig. 7 is a side elevation of a modified or portable form of the invention.

Fig. 8 is a fragmentary plan view of a modified form of the invention adapted for inexpensive manufacture.

In detail the construction illustrated in the 45 drawings, referring to Fig. 1, comprises the base 1, having the standard 2 fixed thereto. This standard extends forward at 3 and has the upper jaw 4 fixed thereto. The bearings 5—6 are formed in the standard and the jaw 4 respectively.

50 The crank shaft 7 is journaled in these bearings and has the intermediate crank pin 8. The operating crank arm 9 is fixed on the shaft 7 and has the convenient swivel handle 10 thereon.

The pitman rod 11 is pivoted at 12 to the crank 55 pin 8 and at 13 to the lower jaw 14. This jaw is

vertically slidable in the overhanging guide 15 which has the integral side braces 15'—15' extending to the lower end of the jaw 4. The jaw 4 and the guide 15 may thus be die cast in one piece, thus imparting the necessary rigidity to the structure. The screws 2' extend through the standard 2 to fix the guide thereto.

The lower end of the jaw terminates in the foot 16 adjacent the shoulder 17 on the lower jaw when the arm 9 is at rest. The inner edge of the foot 16 is chamfered to form the laterally projecting shoulder 16'. The space between the chamfered edge of the foot 16 and the shoulder 17 is substantially equal to the width and the height of the locked seam X which forms a flange around 70 the upper edge of a can and locks the cover X' to the body X'' of the can (see the dotted lines in Fig. 6).

The lower jaw 14 has the upper and lower shoulders 17 and 17' which lie in the same lateral plane. The edge of the shoulder 17 lies at a higher level than the shoulder 17' and is adapted to be raised above the shoulder 16' on the foot 16 by the rotation of the crank arm 9 (see Fig. 5). The lower shoulder 17', however, only rises to the 80 extent shown in Fig. 6 beneath the plane of the shoulder 16'.

The bottom of the can rests upon the vertically adjustable bracket 18. This bracket has the head 19 slidable freely up and down the standard 85 2, with sufficient play to cause it to cramp and remain in adjusted position when pressure is applied downward at 18. This bracket is flanged at 20 to align the side of the can with the vertical opening between the jaws 16—17.

90 This invention operates substantially as follows: The flange X is inserted between the foot 16 and the shoulder 17 so that the foot rests upon the top X' of the can on the inner side of the flange and the shoulder 17 bears against the under side of the flange. The bracket 18 is then lifted until it will support the bottom of the can when it is opened and during the opening operation.

95 Turning the crank 9, by means of the handle 10, causes the shoulder 17' of the reciprocating jaw 14 to lift against the resistance of the chamfered edge of the jaw 4 and seats the shoulder 16' upon the upper edge of the flange X. This partially unfolds the flange and bends it outward as shown at X''' in Fig. 6.

100 The can is slightly rotated on the platform 18 by the operator, between the reciprocations of the lower jaw 14, to feed the flange X between the working jaw and the foot 16, as the opening 110

progresses. In the second stage of the unfolding of the flange, the bent out portion X''' is engaged by the shoulder 17 of the working jaw. This uncurls the flange and strips it upward against the side of the shoulder 16' as shown in Fig. 5.

This unfolding of the flange X unlocks the cover X' from the body X'' of the can without cutting any metal or exposing the contents of the can during the opening operation. The cover X' being still intact, may be used as a lid to protect the contents until used.

If the planes of the shoulders 17 and 17' are made slightly oblique to the plane of the foot 16, as shown in Fig. 2, the shoulders will exert a tilting pressure against the flange X , which reduces the resistance to the unfolding action.

The modification shown in Fig. 7 operates as described to open a can, but differs in construction. The jaws 4x and 14x, have the opposed overlapping ends 16x and 17x respectively, that operate on the flange X in the same manner as their counter parts 16-17, as above described.

These jaws are actuated in parallelism by the opposed handles 21-22 which are pivoted together at 23, and have their opposite ends pivoted to their respective jaws at 24-25. The inner ends of the jaws are slotted at 26-27 respectively, to engage the transverse pins 28-29 extending across the U section of the handles 21-22, in the manner of the conventional parallel jaw pliers.

The spring 30 contracts between its anchor 31 in the handle 22 and the end 32 of the jaw 14x, to maintain the jaw ends 16x-17x normally separated, as shown. In using the modified opener, the can is preferably set upon a table and held by one hand of the operator, who grasps the handles 21-22 in the other hand. The jaw ends 16x-17x are then placed over the flange X with the jaw 4x upward. Compressing the handles 21-22 reciprocates the jaws 4x-14x, which unfolds the flange X as previously described, as the can is rotated between the jaw ends.

By sacrificing the parallel action of the jaws the cost of production can be lowered by crossing the handles 33-34 on the pivot 35, scissors fashion, as shown in Fig. 8. The jaw 4xx has the depending end 16xx opposed to the end 17xx on the jaw 14xx. This form would be operated with the handles tangential to the circumference of the can. The same effect could be obtained by offsetting the jaw ends 16x-17x at 90° to the plane of the handles 21-22.

Having thus described this invention, what is claimed and desired to secure by Letters Patent is:

1. An opener for cans having interlocked

seams, including an upper jaw adapted to engage over the top of a can and abut the interlocked seam and having a shoulder projecting laterally therefrom above the lower edge thereof and adapted to engage over the top of the seam, a lower jaw spaced laterally from said upper jaw and consisting of two longitudinally arranged shoulders of varying height and adapted to engage under the interlocked seam, and means for moving said lower jaw with respect to the upper jaw to unfold the interlocked seam. 80

2. An opener for cans having interlocked seams, comprising a fixed standard, an upper jaw secured to said standard and adapted to engage over the top of a can and abut the interlocked seam and having a shoulder projecting laterally therefrom above the lower edge thereof and adapted to engage over the top of the seam, a lower jaw spaced laterally from said upper jaw and said shoulder and slidably guided on said standard and adapted to engage under the interlocked seam, and means for raising the lower jaw above the level of said shoulder to unfold the interlocked seam. 85

3. An opener for cans having interlocked seams, comprising a fixed standard having a forward extension at its upper end, an upper jaw secured to said extension and depending therefrom and adapted to engage over the top of a 90 can and abut the interlocked seam and having a shoulder extending laterally therefrom above the lower edge thereof and adapted to engage over the top of the seam, a guide fixed to said standard and integrally connected to said upper 95

jaw, a lower jaw slidably mounted in said guide and spaced laterally from said upper jaw and said shoulder and adapted to engage under the interlocked seam, a revolvable crank pin mounted on said standard, a manually operable crank adapted to revolve said crank pin, a pitman connecting said crank pin and said lower jaw and adapted to raise said lower jaw above the level of said shoulder to unfold the interlocked seam. 100

4. An opener for cans having interlocked 105 seams comprising a lower jaw adapted to engage under the interlocked seam; an upper jaw having a foot spaced laterally from said lower jaw substantially less than the thickness of said seam, and having a shoulder projecting laterally therefrom above the level of said foot and spaced from said lower jaw a distance substantially equal to the thickness of said seam when unfolded; and means for raising said lower jaw above the level of both said foot and shoulder of said upper jaw. 110
